CLAIM

The ornamental design for an ambient air impeller for
igniting briquets or the like, as shown and described.

DESCRIPTION

FIG. 1 is a top plan view of an ambient air impeller, for
igniting briquets, or the like showing my new design;

FIG. 2 is a bottom plan view thereof;

FIG. 3 is a front elevational view thereof;

FIG. 4 is a rear elevational view thereof;

FIG. 5 is a side elevational view thereof;
FIG. 6 is a side elevational fragmented view of the
handle of the claimed design, with the hook extended;
and

FIG. 7 is a rear elevational view of an alternative rear
embodiment.

FIG. 3

FIG. 1

FIG. 2

FIG 6

FIG. 7
